SIGN

Guglielmo Angeli, New York, N. Y.

Application September 26, 1932, Serial No. 634,940

5 Claims. (Cl. 40—133)

This invention relates to luminous signs and more particularly refers to improvements in signs of the type where a transparent multi-colored screen is interposed between a source of light and a display panel also carrying transparent or translucent display matter.

The primary object of this invention is to provide a luminous sign of a novel and improved construction, whereby attractive multi-colored lighting effects can be obtained with relatively simple and inexpensive means.

Another object is to provide a luminous sign of a simple and relatively inexpensive construction, adapted to produce novel and attractive multi-colored lighting effects of a soft, mellow and pleasing character, comparable to the luminous effects produced by means of tubes containing rarefied gases, such as neon tubes.

Other objects and advantages of the present invention will more fully appear as the description proceeds and will be set forth and claimed in the appended claims.

The sign forming the subject of the present invention is, to a certain extent, similar to another type of luminous sign such as has been described and claimed by me in a copending application, entitled "Luminous sign", Serial No. 529,234. The similarity resides in that novel and pleasing luminous effects are obtained by interposing a movable screen, comprising a plurality of multi-colored transparent or translucent members between a source of light and a display panel, said display panel having displays cut out to form openings, which are filled by transparent or translucent elements, preferably made of glass, having a curved or round cross section.

The present construction, however, is much simpler and permits of producing an effective display device at a relatively much lower cost than that entailed by a construction such as advocated in my other application, above referred to.

My invention is illustrated by way of example in the accompanying drawing, in which:

Fig. 1 is a front view in elevation of a sign embodying my invention;

Fig. 2 shows a vertical section thereof with parts broken away;

Fig. 3 is a horizontal section thereof;

Fig. 4 shows a detail, showing one of the possible ways of mounting the transparent or translucent elements onto the rotating screen;

Fig. 5 shows another detail, illustrating one of

the possible manners of fastening the transparent fillers onto the display panel;

Fig. 6 shows a fragmentary detail, illustrating the possibility of using hollow transparent elements in place of the solid transparent elements shown in Figs. 4 and 5, said hollow transparent elements being adapted to be filled with liquids of different colors, and

Fig. 7 shows a vertical section of a hollow letter, adapted to be filled with liquids of different colors, for use in place of the letters shown in Fig. 1.

Referring to Figs. 1 to 5, 10 designates a casing, having at the front a display panel 11, with cut-out letters or signs or decorations, and provided with transparent or translucent members, such as 12, filling up the openings thus produced.

Said transparent elements may be constituted by solid glass rods, as shown in Fig. 5, said rods being shaped to conform with the outline of letters or signs to be displayed, and being secured onto the panel by means of wire clips 13, or in any other suitable manner, or else said transparent elements may be in the nature of letters or signs cast or molded in the proper shape out of transparent or translucent material, such as, for instance, glass.

Within the casing and directly behind the display panels is rotatably mounted the screen 14, carried by a shaft 15. Said screen consists of a diaphragm 16, having a circumferential series of radial openings, adapted to receive transparent or translucent elements or bars 17, made of glass or other suitable material, said bars being of different colors, so as to cause the light filtering through them to produce varying colorations of the transparent or translucent display matter carried by panel 11.

Light sources represented by bulbs 18 are provided at the rear of the rotating screen, and in order to obtain a soft glow, comparable to that produced by rarefied gas tubes, it is preferable for the transparent elements of both screen and display panel that the same be constituted by solid glass bars. However, it is within the scope of my invention to use transparent elements of a different character, if desired.

For instance, in my improved type of sign I prefer to use either in connection with the screen or with the display panel, or both, hollow transparent elements, such as shown at 19, in Fig. 6, said hollow transparent elements being provided with a closure, such as a stopper 20, and being, therefore, adapted to be filled with liquids of different colors. Such a construction makes it pos-

sible to alter the color effects at will, merely by changing the color of the liquids contained in the various transparent elements.

The screen can be made to rotate in any suitable manner. For instance, the outer rings 21, 22, shown in Fig. 4 as being fastened onto the diaphragm 16 by means of screws 23, may form together with said diaphragm a rim adapted to receive a belt 24, by means of which said screen 10 may be rotated, said belt being actuated by an electric motor 25, and being preferably maintained under tension by a tensioning device, such as 26.

In Fig. 7 I show by way of example a hollow transparent or translucent letter 28, provided with a stopper 27, adapted to be used in connection with the front panel, as shown in Fig. 1, the color effects of said panel being thus made variable by filling its letters or displays with liquids of 20 different colors.

It is, of course, within the scope of my invention to rotate the screen in any desired manner, the inventive idea proper residing in the provision of an extremely simple display device, 25 where the transparent or translucent screen is constituted by a disk carried by a rotatable shaft; the result being a compact, effective and inexpensive construction.

The transparent members may have a circular, 30 oval, square, hexagonal or other sections and each of them may be of the same color or may be subdivided into parts of different colors. The differently colored rods when passing along the transparent bodies of the letters or signs produce 35 colored light variations of a most agreeable appearance.

It is obvious that although glass rods are to be preferred because of the vividness of the effects produced thereby, it is within the scope of my invention to use transparent colored units made of 40 material other than glass.

It is obvious also that the invention may be carried into practice in a number of ways different from those shown and described. The 45 drawing will, therefore, be understood as being intended for illustrative purposes only and not in a limiting sense.

I accordingly reserve the right to apply my invention in all those ways and manners which 50 may enter, fairly, into the scope of the appended claims.

I claim:

1. In a luminous sign the combination, with a 55 casing comprising an opaque panel having display matter permitting the passage of light therethrough, and a source of light within said casing, of a rotatable shaft, a multicolored screen interposed between said source of light and said

panel, carried by said shaft, said screen comprising a plate having a circumferential series of openings, and bar shaped units of different colors permitting the passage of light inserted and retained within said openings. 5

2. A luminous sign of the character described, comprising a casing, an opaque panel having cut-out display matter in front of said casing, fillers permitting the passage of light inserted in the resulting display openings, a source of light within said casing, a horizontal shaft rotatably mounted within said casing, and a screen interposed between said source of light and said panel, carried by said shaft, said screen comprising a 10 disc having a circumferential series of openings, and bar shaped units of different colors permitting the passage of light inserted and retained within said openings. 15

3. A luminous sign of the character described, 20 comprising a casing, an opaque panel having cut-out display matter in front of said casing, fillers permitting the passage of light inserted in the resulting display openings, a source of light within said casing, a shaft rotatably mounted 25 within said casing, a screen interposed between said source of light and said panel, said screen comprising a disc having a circumferential series of openings, and bar shaped multicolored units permitting the passage of light inserted and retained within said openings, and means for 30 rotating said shaft.

4. A luminous sign of the character described, 35 comprising a casing, an opaque panel having cut-out display matter in front of said casing, multicolored fillers permitting the passage of light inserted in the resulting display openings, a source of light within said casing, a shaft rotatably mounted within said casing, and a screen 40 interposed between said source of light and said panel, carried by said shaft, said screen comprising a disc having a circumferential series of substantially radial openings, and bar shaped units of different colors permitting the passage of light inserted and retained within said openings. 45

5. A luminous sign of the character described, comprising a casing, an opaque panel having cut-out display matter in front of said casing, multicolored fillers permitting the passage of light inserted in the resulting display openings, a source of light within said casing, a shaft rotatably mounted within said casing, and a screen interposed between said source of light and said panel, carried by said shaft, said screen comprising a disc having a circumferential series of substantially radial openings, and bar shaped multicolored units permitting the passage of light inserted and retained within said openings. 50 55

GUGLIELMO ANGELI.
